FIG. 1 is a top plan view of the reed for a reed switch showing my new design;

FIG. 2 is a front side elevational view thereof;

FIG. 3 is a rear side elevational view thereof;

FIG. 4 is a left side elevational view thereof;

FIG. 5 is a right side elevational view thereof; and

FIGS. 6 through 12 are top plan views of modified forms of the reed described in FIG. 1 showing my new design.

The bottom plan views opposite to the top plan views of FIGS. 6 through 12 and 1 are identical to these respective figures. The front rear right side and left side elevational views of the reeds shown in FIGS. 6 through 12 are identical to FIGS. 2, 3, 4, and 5, respectively. The tongues

of FIGS. 1, 6, 7, 8, 9, 10, 11 and 12 include areas on either side thereof concavely depressed from the planar surface.

I claim:

The ornamental design for a reed for a reed switch, as shown and described.
